(57) **CLAIM**

The ornamental design for a group writing device, as shown and described.

DESCRIPTION

FIG. 1 is a top, perspective view of a group writing device in accordance with the present invention;

FIG. 2 is a front view of the group writing device, of FIG. 1;

FIG. 3 is a right-side view of the group writing device of FIG. 1;

FIG. 4 is a left-side view of the group writing device of FIG. 1;

FIG. 5 is a rear-side view of the group writing device of FIG. 1;

FIG. 6 is a top view of the group writing device of FIG. 1;

FIG. 7 is a bottom view of the group writing device of FIG. 1;

FIG. 8 is a bottom, perspective view of the group writing device of FIG. 1;

FIG. 9 is a top view of an axle portion of the group writing device of FIG. 1;

FIG. 10 is a bottom view of the axle portion of FIG. 9;

FIG. 11 is a left-side view of the axle portion of FIG. 9;

FIG. 12 is a right-side view of the axle portion of FIG. 9;

FIG. 13 is a front view of the axle portion of FIG. 9;

FIG. 14 is a rear view of the axle portion of FIG. 9;

FIG. 15 is a top, perspective view of the axle portion of FIG. 9;

FIG. 16 is a top view of a lower plate portion of the group writing device of FIG. 1;

FIG. 17 is a bottom view of the lower plate portion of FIG. 16;

FIG. 18 is a front view of the lower plate portion of FIG. 16;

FIG. 19 is a rear view of the lower plate portion of FIG. 16;

FIG. 20 is a right-side view of the lower plate portion of FIG. 16;

FIG. 21 is a left-side view of the lower plate portion of FIG. 16;

FIG. 22 is a top, perspective view of the lower plate portion of FIG. 16;

FIG. 23 is a top view of an upper plate portion of the group writing device of FIG. 1;

FIG. 24 is bottom view of the upper plate portion of FIG. 23;

FIG. 25 is front view of the upper plate portion of FIG. 23;

FIG. 26 is rear view of the upper plate portion of FIG. 23;

(Continued)

FIG. 27 is right-side view of the upper plate portion of FIG. 23;

FIG. 28 is left-side view of the upper plate portion of FIG. 23;

FIG. 29 is a top, perspective view of the upper plate portion of FIG. 23; and,

FIG. 30 is a perspective view of the group writing device of FIG. 1 including a writing device in the axle portion and the lower plate portion coupled to guiding strings.

The broken lines in the drawings illustrate environmental subject matter and form no part of the claimed design.

The claim is directed to the collective appearance of all elements shown in the figures.
